US00D969070S

(12) **United States Design Patent** (10) **Patent No.:** **US D969,070 S**
(45) **Date of Patent:** **** Nov. 8, 2022**

(54) **POWER SUPPLY**

(71) Applicant: **Shenzhen Intelligent Energy Co., Ltd,** Shenzhen (CN)

(72) Inventor: **Huayan Fang**, Guangdong Province (CN)

(**) Term: **15 Years**

(21) Appl. No.: **29/750,531**

(22) Filed: **Sep. 15, 2020**

(30) **Foreign Application Priority Data**

Aug. 14, 2020 (CN) 202030463669.0

(51) **LOC (13) Cl.** **13-02**

(52) **U.S. Cl.**

(57) **CLAIM**

The ornamental design for a power supply, as shown and described.

DESCRIPTION

FIG. 1 is a front elevation view of a power supply, showing my new design;

FIG. 2 is a top plan view thereof;

FIG. 3 is a bottom plan view thereof;

FIG. 4 is a rear elevation view thereof;

FIG. 5 is a left side elevation view thereof;

FIG. 6 is a right side elevation view thereof; and,

FIG. 7 is a top, front, right side perspective view thereof. The broken lines in the drawings depict portions of the power supply that form no part of the claimed design.
